WILLIAM F. HAUPT, OF ORANGE, NEW JERSEY, ASSIGNOR OF ONE-HALF TO CLARENCE S. A. WILLIAMS, OF SOUTH ORANGE, NEW JERSEY.

THREAD-SPINNING MACHINE.

1,407,793.

Specification of Letters Patent. Patented Feb. 28, 1922.

Application filed May 17, 1921. Serial No. 470,378.

To all whom it may concern:

Be it known that I, WILLIAM F. HAUPT, a citizen of the United States, and a resident of the city of Orange, Essex County, 5 New Jersey, have invented certain new and useful Improvements in Thread-Spinning Machines, of which the following is a description.

My invention relates to thread spinning machines and more particularly to improvements in the feed roller mechanisms which feed the fine threads downwardly from their respective spools to the spinning devices in such machines.

In the manufacture of spun threads as it has heretofore been carried on, considerable wastage of material results from the breaking of the fine single threads which are finally spun into the finished thread. This 15 is principally due to the frictional wear on the thread by its engagement with the feed rollers of the feed roller mechanisms and with the aligning or spacing bar which is located between and above such feed rollers, and to the fact that the ends of the threads, once they are broken, are likely to 20 come in contact with and be drawn into the gearing of the feeding mechanism. The losses which are thus caused are very appreciable, and where the spun threads are of 25 high grade, expensive material, such as silk, are extremely serious. Moreover, much of the spun or finished thread manufactured 30 at the present time is very imperfect due to the wearing, catching and tearing of the thread by reason of its engagement with the feed rollers and the aligning and spacing bar referred to above.

Among the principal objects of my invention are to prevent practically all wastage and losses such as above described, and to produce the finished spun thread, especially 35 in the case of silk thread, in substantially perfect condition, or at least to a degree of 40 perfection heretofore unattained.

My invention further contemplates an improved construction for attaining the foregoing objects, which is preferably in the form of an attachment capable of being 45 readily applied to spinning machines now in use. Such attachment is preferably removably mounted so as to be readily replaceable, and also preferably mounted for such adjustment as may be necessary to ensure the proper meshing or engagement of

the feed roller gears with the corresponding driving gear.

Other objects and features of my invention will be hereinafter more fully described and claimed. 60

In order that my invention may be more clearly understood, attention is directed to the drawing accompanying and forming a part of this specification, and in which:

Figure 1 is a view in front elevation, 65 partly in section, of one of the feed roller mechanisms of a silk spinning machine illustrating the application of my invention thereto;

Fig. 2 is a sectional view, partly in elevation, taken on line 2'-2' of Fig. 1, looking in the direction of the arrows; 70

Fig. 3 is a sectional view taken on line 3', 3' of Fig. 1, looking in the direction of the arrows; 75

Fig. 4 is an enlarged view in front elevation of one of the feed roller gears of the feed roller mechanism shown in Figs. 1, 2 and 3;

Fig. 5 is a view looking from the right 80 in Fig. 4;

Fig. 6 is an enlarged central, longitudinal, cross-sectional view of one of the feed roller gears with the feed roller mounted thereon; 85 and

Fig. 7 is an enlarged detailed view, partly in elevation and partly in section, of my improved spacing and aligning bar and its mounting.

Referring to the drawing 1, 1 represent 90 the fine, raw, silk threads, which are respectively drawn from spools (not shown) on the spinning machine through tripper hooks (not shown), and then pass together down through the usual porcelain guide 2 which 95 is supported on one end of an arm 3 adjustably secured to the usual vertical tripper rod 4, as by means of a collar 5 and set-screws 6. From the guide 2 the threads are conducted in the form of a single or 100 combined thread 8 over horizontal feed rollers 7 and downwardly to the usual spinning device (not shown), and formed into the finished spun thread. Three or four turns of the combined thread 8 are made 105 around the feed rollers 7, 7, and over a porcelain spacing and aligning hook or bar 9, which is disposed substantially midway between and slightly above the feed rollers. The hook or bar 9 while substantially hori- 110

- zontal, has a slight downward inclination and serves as a guide to maintain the thread 8, in its several turns around the feed rollers, properly spaced and aligned. Two gears or 5 pinions 10, 10, which serve to drive the feed rollers 7, 7, are normally in engagement with and driven by a gear 11 fixed to the main horizontal driving shaft 12 of the machine. The feed rollers 7, 7, feed roller 10 gears 10, 10 and the spacing and aligning bar or hook 9 are all carried by a frame 13 secured to the vertical tripper rod 4 in a manner which will be hereinafter described.
- 15 In case any of the fine raw threads 1, 1 breaks, the tension on the corresponding tripper hook (not shown) is released, the latter drops and in turn releases the tripper rod 4, whereupon the tripper rod is automatically raised or thrown up, carrying with it the frame 13, and thereby effecting the disengagement and separation of the feed roller gears 10, 10 and the driving gear 11, in a manner well understood. In order 20 to ensure the proper engagement or meshing of the feed roller pinions 10, 10 with the driving gear 11 and also to render it extremely easy to replace the frame 13 and the parts carried thereby in case of breakage, wear or other damage, the frame is 25 adjustably and also removably mounted on the tripper rod 4. As illustrated, this is accomplished as follows: The frame 13 is provided at the top with a projection in the 30 form of a horizontal guide 14, and a collar 15 rigidly attached to the rod 4, as by means of a set-screw 16, has a lateral extension or bracket 17 provided on its under side with a horizontal guide-way 18 with which the 35 guide 14 engages. A screw 19 extends through a slot 20 in the extension 17 and is threaded into the projection 14 of the frame 13. The loosening of screw 19 permits the frame 13 to be easily adjusted to 40 properly mesh the gears 10, 10 with the driving gear 11 and upon then tightening the screw 19 the frame will be rigidly secured in adjusted position. To remove the frame 13 and parts carried thereby it is 45 merely necessary to loosen the screw 19 sufficiently to disengage the same from the guide or projection 14. The frame 13 may accordingly be easily and quickly replaced by a similar frame carrying like parts, 50 without involving the necessity of moving the tripper rod 4 from its normal position in the spinning machine.
- The feed rollers heretofore used in mechanisms of the character shown and described herein, have usually been made of steel. Such rollers, however, are easily worn by silk and consequently the surfaces thereof quickly roughen and then wear, tear and catch the fine silk threads or fibres. These deleterious effects are further increased by 55 reason of the static electricity which results from the friction between the steel feed rollers and the silk threads. Consequently, the silk thread heretofore produced has usually been far from perfect. In order to 60 obviate these defects the employment of porcelain rollers has been proposed, but in so far as I am aware, no practicable construction for such rollers and for connecting the same to the feed roller gears has heretofore been suggested. I have designed such a construction, however, which is best illustrated in Figs. 2, 4, 5 and 6 and which I shall now describe. The feed roller gears 10, 10 are rotatably mounted on steel rods 65 21 driven at one end into the frame 13, and each of these gears is provided with a long, laterally extending hub 22, which is irregular in cross-section and through which the rod 21 extends. Preferably the hubs 22 are 70 square in cross-section, although such cross-section may be hexagonal, elliptical or of other non-circular shape. The hubs 22 are also preferably tapering, and thus when 75 square in cross-section, as shown, they will 80 have the form of truncated pyramids. The cylindrical feed rollers, 7, 7 are made of porcelain and molded with axially extending openings which substantially correspond 85 in shape and size with the gear hubs 22. 90 Porcelain rollers provided with such openings may be very readily molded. Each of the rollers 7, 7 is kept in place on the respective gear as by means of a screw 23 threaded into the outer end of the corresponding rod 21 and a washer 24 disposed 95 between the head of the screw and the adjacent ends of the gear hub and roller, the outer end portion of each roller preferably being recessed as indicated at 100 to receive 105 the washer and the head of the screw. By reason of the cross-sectional shape and taper of hubs 22 and the openings through rollers 7, 7, the latter may be pushed tightly onto the gear hubs, and when the screws 23 and 110 washers 24 are applied, are firmly held against any rotary movement with respect to the gears 10, 10 without danger of the 115 rollers being broken.
- Porcelain thread aligning and spacing bars have heretofore been used in mechanisms of the character described herein, but prior to my invention it has been necessary to frequently replace these bars as they are often broken. In addition to the expense and trouble directly involved in such 120 replacements, this results in serious losses in the time of operation of machines provided with such bars. The reason for the frequent breaking of these bars is probably 125 due to the fact that they are of small cross-section and have usually been mounted on the feed roller frames by securing one end thereof directly in openings provided therefor in such frames. In order to obviate 130

this objection, I provide a guiding and spacing bar 9 (referring to Fig. 7), preferably in the form of a hollow cylindrical tube provided with an outer hook end 26. This 5 bar 9 is secured to the frame 13 by a headed rod 27, preferably of steel or other metal, which extends through and fits loosely within the opening through the bar, and which is threaded into an opening 28 in the 10 frame. A cushioning member such as a slightly yieldable washer 29, preferably of leather, is disposed between the frame 13 and the inner end of the bar 9, and the rod 27 is turned up until the inner end of the 15 bar firmly engages the washer 29 and the outer end thereof is firmly engaged by the head of the said rod, so that the bar will be securely held in the position shown. It will be apparent that transverse strains on 20 the bar 9 will be transmitted to the metal rod 27 and that the danger of this bar being broken in the operation of the machine is therefore extremely slight.

Another and a very important feature of 25 my invention resides in the construction for effectually preventing the threads being drawn into the gearing in case, for example, any of the fine threads breaks and the frame 13 is automatically moved upwardly to dis- 30 engage and space the feed roller gears 10, 10 from the driving gear 11, as explained above. For this purpose I preferably form the frame 13 as a hollow guard for the feed roller gears 10, 10 and driving gear 12, by 35 providing the same with imperforate top and vertical side, and rear walls, and a vertical front wall 30 having only a pair of circular openings 31, which are only a very little greater in diameter than the feed 40 rollers and through which the inner end portions of these rollers extend. A hollow guard 32 member formed with top, front and rear walls is also provided for covering that portion of the driving shaft 12 below and 45 adjacent the feed rollers 7, 7, this member extending a considerable distance forwardly from the vertical front wall 30 of the frame 13 substantially at right angles thereto and being rigidly secured to the frame so as to 50 move upwardly therewith when the same is automatically raised by reason of the thread breaking. Preferably, the guard member 32 is made an integral part of the frame 13. The rear guard wall 33 of frame 13 is slotted 55 at 34 so as to straddle the shaft 12, and while the guard comprising the frame 13 and member 32 is open at the bottom, all of its walls, with the exceptions noted, are solid or imperforate, and all of its vertical walls 60 extend down a considerable distance below the shaft 12. Accordingly, every part of the gearing and the driving shaft 12 with which broken ends of thread passing through the feed roller mechanism are at all likely to 65 come into contact, are completely enclosed or

covered at all times, regardless of whether the frame 13 and the parts carried thereby are in lowered or raised position. Losses due to broken threads being drawn into and entangled with such gearing and driving 70 shaft are thus completely and effectually eliminated. In the construction shown, the frame 13 with its top, side, front and rear walls and the guard member 32 formed integrally with the front wall 30 of the frame, 75 constitute an integral one-piece guard.

It will be seen that the frame 13 and the parts carried thereby, which embody practically all features of my invention, comprise an attachment capable of being readily 80 applied to spinning machines in use. Such attachment when once applied to a machine is also capable of being quickly and easily replaced and may be readily adjusted on such machine for the purposes hereinbefore 85 described.

While I have shown and described my invention as applied to a silk spinning machine, it is not limited in its application either to machines for spinning silk thread 90 or to spinning machines of any particular form or construction. It is also to be understood that the various features of my invention are subject to various modifications and changes in the number, size, shape and 95 arrangement of parts without departure from the spirit of my invention and the scope of the appended claims.

Having now described my invention, what I claim and desire to protect by Letters Pat- 100 ent is as follows:

1. In a thread spinning machine, a driving gear, a feed roller frame, and feed rollers and feed roller gears carried by said frame, said frame being movable with respect to said driving gear so as to move said feed roller gears into and out of engagement with the driving gear, said frame and driving gear being relatively adjustable to ensure the proper meshing of the feed roller 105 gears with the driving gear.

2. In a thread spinning machine, a shaft carrying a driving gear, a tripper rod, a feed roller frame supported by said tripper rod, and feed rollers and feed roller gears 110 carried by said frame, said feed roller gears being adapted for engagement with said driving gear, said frame being adjustable with respect to the tripper rod to ensure the proper meshing of the feed roller gears with 115 the driving gear.

3. In a thread spinning machine, the combination with a tripper rod and a shaft carrying a driving gear, of a feed roller frame, and feed rollers and feed roller gears adapted for engagement with said driving gear carried by said frame, said frame being mounted on said tripper rod so as to be readily removable therefrom without moving 125 said rod from its normal position in the ma- 130

- chine to thereby enable the frame and the parts carried thereby to be readily replaced.
4. In a thread spinning machine, the combination with a tripper rod and a shaft carrying a driving gear, of a collar on said tripper rod, a feed roller frame, and feed rollers and feed roller gears adapted for engagement with said driving gear carried by said frame, said frame being mounted on said collar to enable the same and the parts carried thereby to be readily replaced.
5. In a thread spinning machine, the combination with a tripper rod and a shaft carrying a driving gear, of a feed roller frame, and feed rollers and feed roller gears adapted for engagement with said driving gear carried by said frame, said frame being mounted on said tripper rod so as to be readily removable therefrom without moving said rod from its normal position in the machine to thereby enable the frame and the parts carried thereby to be readily replaced, said frame also being adjustable with respect to the tripper rod to ensure the proper meshing of the feed roller gears with the driving gear.
6. In a thread spinning machine, the combination with a tripper rod and a shaft carrying a driving gear, of a feed roller frame, and feed rollers and feed roller gears adapted for engagement with said driving gear carried by said frame, a thread spacing and aligning bar carried by said frame and disposed above and between the feed rollers, said frame being mounted on said tripper rod so as to be readily removable therefrom without moving said rod from its normal position in the machine to thereby enable the frame and the parts carried thereby to be readily replaced.
7. In a thread spinning machine, the combination with a tripper rod and a shaft carrying a driving gear, of a feed roller frame, and feed rollers and feed roller gears adapted for engagement with said driving gear carried by said frame, said frame being provided with a guard covering the feed roller gears and driving gear and having a forwardly extending portion covering said shaft adjacent the said gears and beneath the feed rollers, said frame being mounted on said tripper rod so as to be readily removable therefrom without moving said rod from its normal position in the machine to thereby enable the frame and the parts carried thereby to be readily replaced.
8. In a thread spinning machine, the combination with a tripper rod and a shaft carrying a driving gear, of a feed roller frame mounted on said rod, and feed rollers and feed roller gears adapted to engage the driving gear, carried by the frame, said frame being provided with a guard covering said feed roller and driving gears, said
- guard comprising a forwardly extending portion covering said shaft adjacent said gears and beneath the feed rollers.
9. In a thread spinning machine, the combination with a tripper rod and a shaft carrying a driving gear, of a feed roller frame mounted on said rod, and feed rollers and feed roller gears adapted to engage the driving gear, carried by the frame, said frame being formed as a guard covering said feed roller and driving gears, said guard having a lateral portion covering said shaft and extending between the shaft and the feed rollers.
10. In a thread spinning machine, the combination with a tripper rod and a shaft carrying a driving gear, of a feed roller frame mounted on said rod, and feed rollers and feed roller gears adapted to engage the driving gear, carried by the frame, said frame being formed as a one-piece guard covering said feed roller and driving gears and also a considerable portion of said shaft adjacent said gears and beneath the feed rollers.
11. An attachment for spinning machines comprising a feed roller frame adapted to be applied to the tripper rod of such a machine, and feed rollers and feed roller gears carried by said frame, said frame being provided with a guard for covering the feed roller gears, said guard having a portion extending forwardly beneath the feed rollers.
12. A feed roller frame for spinning machines formed to substantially enclose the feed roller gears so as to provide a thread guard between such gears and the feed rollers, the frame also being provided with a laterally extending portion beneath the feed rollers to provide a thread guard between said rollers and the driving shaft of the machine.
13. In a thread spinning machine, the combination of a feed roller frame, feed rollers carried by said frame, a spacing bar of porcelain disposed above said feed rollers, said bar having a longitudinal opening extending therethrough, and a headed member extending through said opening in said bar and secured to said frame whereby the bar is attached to the frame.
14. In a thread spinning machine, the combination of a feed roller frame, feed rollers carried by said frame, a spacing bar of porcelain disposed above said feed rollers, said bar having a longitudinal opening extending therethrough, a headed member extending through said opening in said bar and secured to said frame whereby the bar is attached to the frame, and a cushioning member disposed between the frame and the adjacent end of the spacing bar.

This specification signed this 13th day of May, 1921.

WILLIAM F. HAUPT.
